US00D883986S

(12) **United States Design Patent** (10) **Patent No.:** **US D883,986 S**
(45) **Date of Patent:** **** May 12, 2020**

(54) **COVER**

(71) **Applicant:** **Apple Inc.**, Cupertino, CA (US)

(72) **Inventors:** **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)

(73) **Assignee:** **Apple Inc.**, Cupertino, CA (US)

(**) **Term:** **15 Years**

(21) **Appl. No.:** **29/656,624**

(22) **Filed:** **Jul. 13, 2018**

(51) **LOC (12) Cl.** **14-02**

(52) **U.S. Cl.**

USPC **D14/440**

(58) **Field of Classification Search**

USPC D14/440, 447, 250; 206/45.23, 320, 206/45.2; 361/679.55; 294/25; 224/218

CPC G06F 1/1628; G06F 1/1626; A47B 23/044

(57) CLAIM

The ornamental design for a cover, as shown and described.

DESCRIPTION

FIG. 1 is a bottom front perspective view of a cover showing the claimed design;

FIG. 2 is a front view thereof;

FIG. 3 is a rear view thereof;

FIG. 4 is a left side view thereof;
FIG. 5 is a right side view thereof;
FIG. 6 is a top view thereof;
FIG. 7 is a bottom view thereof;
FIG. 8 is a side view of the cover in an environment in which it may be used;
FIG. 9 is another side view of the cover in an environment in which it may be used;
FIG. 10 is another side view of the cover in an environment in which it may be used;
FIG. 11 is a bottom front perspective view of another embodiment of a cover showing the claimed design.
FIG. 12 is a front view thereof;
FIG. 13 is a rear view thereof;
FIG. 14 is a left side view thereof;
FIG. 15 is a right side view thereof;
FIG. 16 is a top view thereof;
FIG. 17 is a bottom view thereof;
FIG. 18 is a side view of the cover in an environment in which it may be used;
FIG. 19 is another side view of the cover in an environment in which it may be used; and,
FIG. 20 is another side view of the cover in an environment in which it may be used.
The broken lines in the figures show environment that forms no part of the claimed design.
